A. Thomas,
Lathe-Way Smoother

N° 70,483.

Patented Nov. 5, 1867.

Inventor;
Alfred Thomas.

United States Patent Office.

ALFRED THOMAS, OF WORCESTER, MASSACHUSETTS.

Letters Patent No. 70,483, dated November 5, 1867.

IMPROVEMENT IN LATHE-WAY SMOOTHERS.

The Schedule referred to in these Letters Patent and making part of the same.

KNOW ALL MEN BY THESE PRESENTS:

That I, ALFRED THOMAS, of the city and county of Worcester, and Commonwealth of Massachusetts, have invented certain new and useful Improvements in Lathe-Way Smoothers; and I do hereby declare that the following is a full, clear, and exact description of the same, reference being had to the accompanying drawings, forming a part of this specification, in which—

Figure 1 represents so much of a planing machine, with my improvements applied thereto, as is necessary to illustrate my invention, and

Figure 2 represents a vertical section through the beds and the arms which support the shaft of the smoothing-wheel.

To enable those skilled in the art to which my invention belongs to make and use the same, I will proceed to describe it more in detail.

In the drawings, A represents the stationary bed of an ordinary planing machine, and B the movable bed, which works on the ways *a a*, and may be moved back and forth in the ordinary manner. C is the frame, which supports the planing-tool, and which also serves to support the lathe-way smoothing apparatus. D is a bed of a lathe arranged upon the movable bed or table B, and fastened thereto by cross-pieces *b* and bolts *c*. The ways *d d* of the bed D have heretofore been finished by a hand-file, an operation both tedious and expensive, but which operation can be performed by my improved mechanism in a very uniform and expeditious manner. To the slide-piece E is fastened the frame F, in the arms G G of which is supported in suitable bearings a shaft, H, having a pulley, I, upon its centre, while its ends extend on either side sufficiently far to support the smoothing and reducing-wheel J. The slide-piece E is dove-tailed to the piece K, which, in turn, is dove-tailed to the cross-piece or bar L. The piece K can be moved upon the cross-bar L to adjust the smoothing and reducing-wheel J to any desired position, and a screw-shaft may be employed for such purpose, the same as in the common planing machine. Frame F is fastened to the piece E by means of the screws or bolts *e f*, the latter passing through the curved groove *g* in the frame F. By loosening the screws or bolts *e f*, frame F can be tipped laterally to adjust the wheel J to work upon any desired angle.

The operation is as follows: The lathe-bed D is fastened upon the movable table or bed B, and the smoothing or reducing-wheel J is properly adjusted, and a rapid motion is then imparted to it by means of a belt running upon the pulley I. Bed or table B is now run so as to carry the lathe-bed D under and in an opposite direction to the motion of wheel J, whereby the latter reduces and smooths one of the ways *d*, after which the wheel J is changed to the other end of shaft H and frame F adjusted to bring the wheel in the proper position to smooth the other way *d*. By means of screw *h*, frame F can be raised or lowered to elevate or lower wheel J, as may be desired. By this adjustment wheel J may be set to reduce the way slightly at first, and then lowered to finish the way, while the bed is run under the wheel the second time. Wheel J may be covered with emery or any other suitable material.

Having described my improvements in mechanism for smoothing lathe-ways; what I claim as new and of my invention, and desire to secure by Letters Patent, is—

1. The combination with the frame C, cross-bar L, piece K, and slide-piece E, of frame F, shaft H, and smoothing-wheel J, substantially as and for the purposes set forth.

2. The combination of the smoothing-wheel J, shaft H, and pulley I with the slide-piece E, substantially as and for the purposes set forth.

ALFRED THOMAS.
